UNITED STATES PATENT OFFICE.

WILLIAM BAYLEY, OF SPRINGFIELD, OHIO.

SWINGING WINDOW-SASH.

1,152,927.

Specification of Letters Patent.

Patented Sept. 7, 1915.

Application filed March 16, 1914. Serial No. 825,125.

To all whom it may concern:

Be it known that I, WILLIAM BAYLEY, citizen of the United States, residing at Springfield, in the county of Clark and 5 State of Ohio, have invented certain new and useful Improvements in Swinging Window-Sashes, of which the following is a specification.

My invention relates to swinging window 10 sashes and particularly to means for supporting such sashes upon a medial axis at points intermediate their extremities.

The construction herein shown and described is a modification of and an improvement upon my invention shown and described in my copending application Serial No. 808,071, filed December 22, 1913.

Window sashes for use in factories, auditoriums and public buildings are frequently 20 constructed in units of great length, in some cases approximating several hundreds of feet. Such sashes as commonly constructed are too heavy to be supported upon trunnions located only at the extreme ends.

25 The present invention is designed to afford means for pivotally supporting such window sashes at various points throughout their length, whereby they may swing about such pivotal connections as a single unit.

30 The object of the invention is to simplify the structure as well as the means and mode of operation of said devices, whereby they will not only be cheapened in construction, 35 but will be more efficient in use, rigidly supported at frequent intervals, easily operated and unlikely to get out of repair.

Referring to the drawings, Figure 1 is a 40 vertical sectional view of the assembled sash and its support. Fig. 2 is an elevation of the assembled sash. Fig. 3 is an elevation of the window frame and pivotal support for the sash viewed from the outside of the building, the sash being removed. Fig. 4 is 45 a similar view of the sash removed from the supporting frame. Fig. 5 is a detail plan view of a portion of the sash removed from the frame. Fig. 6 is a vertical sectional view of the assembled sash similar to Fig. 1, 50 the construction differing therefrom through the fact that the struts and supports are connected to both the cap and the sill of the window opening. Fig. 7 is a longitudinal sectional view through one of the pivotal 55 connections of the window and its support,

showing the relative positions of the bearing heads and the oscillatory trunnion head. Fig. 8 is a detail sectional view on the line *a—a* of Fig. 7. Fig. 9 is a detail sectional view on line *b—b* of Fig. 7. Figs. 10 and 11 60 are detail views of the bearing head as employed in a construction shown in Figs. 1 and 6 respectively. Fig. 12 is a detail view of the trunnion head adapted to be secured to the transverse horizontal sash bars at a 65 point intermediate the vertical sash bars. Fig. 13 is a detail view of the terminal bearing head adapted to be secured to the window frame. Fig. 14 is a detail view of the trunnion head adapted to be secured to the 70 vertical sash bars as hereinafter described. Fig. 15 is a side view of the trunnion head shown in Fig. 12.

Like parts are indicated by similar characters of reference throughout the several 75 views.

In the drawings 1 and 2 are top and sill bars respectively of the window opening upon which the swinging sash abuts when in closed position. In the form of device 80 shown in Fig. 1 the swinging sash is supported wholly upon standards projecting upward from the sill 3 of the window opening, while in the construction shown in Fig. 6 the standards or struts are connected both 85 to the sill 3 and to the cap 1.

The swinging sash may be of any desired construction or proportion. That shown in the drawings being of the metallic type employing vertical sash bars 4 and 90 transverse sash bars 5 upon which the glass is supported in the usual manner.

In the present construction the sash is formed in two sections, an upper section and a lower section, which are rigidly connected 95 together and swing in unison about a transverse axis intermediate the two sections. Each of the said sections for convenience of manufacture and assembling may be formed in a plurality of units rigidly connected one 100 to the other as shown in Figs. 2 and 5. In such case the vertical sash bars 4 will be doubled at the juncture of succeeding units as indicated at 6 in said figures. The longitudinal sash bars at the margins of the 105 upper and lower sections adjacent to the axis of oscillation are preferably formed from channel bars as indicated at 7, Figs. 1, 6, 8 and 9. Likewise the vertical sash bars 4 at the juncture of succeeding units are 110

formed from similar channel irons as indicated at 8, Figs. 2 and 5.

The upper and lower sections of the sash are spaced one from the other and are connected at intervals throughout their length by intermediate trunnion heads 9. These trunnion heads 9 are disk like members as shown in Figs. 7, 9, 12 and 14 having outwardly projecting concentric studs or trunnions 10 adapted to engage stationarily located bearing heads hereinafter described.

The trunnion heads may be of two different styles or forms as shown in detail in Figs. 12 and 14. The trunnion head as shown in Fig. 14 is provided with oppositely disposed arms 11 adapted to be riveted or bolted to the vertical sash bars 4 of the upper and lower section of the window sash. This style of trunnion head is adapted to be used at each terminal of the sash and at intermediate points coincident with the doubled sash bars at the juncture of succeeding units of the respective sections. This is particularly shown in Fig. 4. In such cases the oppositely disposed arms 11 are bolted to the vertical sash bars in such positions that the heads 9 with their trunnions 10 will be located intermediate the upper and lower sections of the sash. At points coincident with the juncture of succeeding units, the oppositely disposed arms 11 are interposed between the adjacent channel bars of succeeding units as indicated at the right in Figs. 4 and 5.

The style of trunnion head shown in Fig. 12 is employed at points intermediate the vertical sash bars and is secured intermediate the upper and lower sections of the sash by means of a bolt or a rivet 12 which passes through a vertical opening 13 in the trunnion head and through corresponding openings in the channel bars 7 of the upper and lower sash sections. The channel bars 7 are preferably reinforced at the points of the engagement of the trunnion head by means of plates 15 riveted to the channel bars as shown in Figs. 7 and 9. The trunnion heads as illustrated in Fig. 12 are provided with shoulders or rabbets 16 in which flanges of the channel bars 7 engage.

The two styles of trunnion heads illustrated in Figs. 12 and 14 have exactly the same function and differ one from the other only in the fact that, that shown in Fig. 14 is provided with the oppositely disposed arms 11 for attachment to the vertical sash bars while the head shown in Fig. 12 is provided with oppositely disposed flat surfaces 60 and the rabbets 16 for attachment to the longitudinal or transverse sash bars. An operating lever 17 may be formed integral with one of the lateral arms 11 of the oscillatory trunnion head or such operating lever may be omitted and the sash oscil-

lated in the usual manner by a link connected directly to the sash structure.

Bearing heads 18, disk like in form and provided with central openings 19 for the reception of the trunnions 10 of the oscillatory trunnion heads are arranged in pairs, the bearing heads of each pair being located on opposite sides of the corresponding oscillatory trunnion head. These bearing heads are provided with oppositely disposed lateral annular flanges 20 over which engage the extremities of tubular spacing members or pipes 21 extending from one bearing head to the other.

In the construction shown in Figs. 1, 2, 3 and 10, the bearing heads 18 are each provided with a single wing 22, having perforations therein for the engagement of bolts or rivets, by which standards or struts 23 may be secured thereto. As shown in Fig. 1 these struts or standards 23 are preferably though not necessarily adjustable longitudinally by means of sleeves and lock nuts 24. The struts or standards are secured at their ends to lugs or brackets 25 supported upon the sill 3 of the window opening. One of the struts is arranged substantially perpendicular while the other strut is arranged at an inclination thereto, thereby firmly bracing the supporting structure. At their upper ends the heads of the struts are interposed between the wings 22 of the bearing heads 18 located on each side of the corresponding trunnion head.

At each terminal of the window a corresponding bearing head 26 is secured to the window frame by means of integral oppositely disposed arms 27 as shown at the left in Fig. 3. This terminal bearing head 26 is provided with a wing 28 corresponding with the wing 22 of the corresponding bearing head 18. Thus at each end of the structure the pair of bearing heads is made up of one head 26 and a head 18, the terminal strut or standard being connected intermediate the wings 28 and 22 of the respective bearing heads. It will thus be seen that the oscillatory trunnion heads which are rigidly connected with sash sections are thus journaled in the bearing heads 18 located on opposite sides of the trunnion head, which heads 18 are rigidly connected by means of the intermediate spacing tubes 21 and the standards or struts 23 into a rigid supporting structure rigidly connected with the window frame and the building structure. The tubular members 21 are of such diameter as to substantially fill the intermediate space between the horizontal channel bars 7 of the upper and lower sash sections, as shown in Fig. 8. The space 29 intermediate the web of the channel bars 7 and the tubular connecting member 21 is preferably though not necessarily filled with suitable resilient material, which will exclude air

and moisture and at the same time permitting easy movement of the sash about the tubular member 21. It will thus be seen that the bearing heads 18 are arranged in 5 pairs with the tubular spacing members 21 interposed between succeeding pairs of bearing heads and the standards or struts 23 connecting the bearing heads one with the other and with the sill of the window opening and the terminal bearing heads 26 connected with the end bars of the window frame forms a rigid supporting frame in which the swinging sash is pivotally mounted by the engagement of 10 the trunnions 10 upon the trunnion heads 9 with the central openings 19 of the bearing heads. The bearing points may be located at various intervals throughout the length of the sash without interfering with the oscillation thereof.

The construction shown in Fig. 6 differs from that previously described only in that the bearing heads 18 are provided with oppositely disposed wings 30 for the engagement of the standards or struts 31, one of which is located upon the inner side of the window and connected at its opposite extremity with the window sill while the other standard or strut is located at the outer side 25 of the window and connected with the top of the window opening. The function of the several parts and the operation of the sash is exactly the same as before described. This double winged bearing head is clearly 30 illustrated in Figs. 9 and 11. This structure embodying a strut located upon the inner and outer side of the window sash and offset in relation one with the other is similar to that described and claimed in my 35 copending application before mentioned.

To prevent the seepage of water through the central opening in the swinging sash, a flashing 36 of sheet metal is secured to the tubular member 21 as shown in Fig. 8. 40 There are also secured to opposite sides of the tubular members 21, longitudinal bars 32 extending the full length of the swinging sash not only to strengthen the supporting structure, but to provide means for the attachment of the screen sections 33. These 45 screen sections 33 are located on opposite sides of the swinging sash and are connected to the cap and the sill of the window opening as shown at 34 and 35 respectively. The inner or adjacent edges of the screen section 50 33 are clamped beneath the longitudinal bars 32, thereby stationarily supporting the screen sections while permitting the free oscillation of the sash to and from its closed 55 position.

From the above description it will be apparent that there is thus provided a device of the character described, possessing the particular features of advantage before enumerated as desirable but which obviously is

susceptible of modification in its form, proportion, detail construction or arrangement of parts, without departing from the principle involved or sacrificing any of its advantages.

While in order to comply with the statute, the invention has been described in language more or less specific as to certain structural features, it is to be understood that the invention is not limited to any specific details, 70 but that the means and construction herein described comprise but one mode of putting the invention into effect, and the invention is therefore claimed broadly in any of its possible forms or modifications within the 75 scope of the appended claims.

Having thus described my invention, I claim:

1. A swinging sash comprising upper and lower sections spaced one from the other, 80 bearing heads connecting the separated sash sections and cylindrical frame members located within the window space between the sash sections and intermediate successive bearing heads to which the said heads 85 are pivotally connected.

2. A swinging sash comprising two sections separated one from the other, bearing heads located between the sash sections connecting them one to the other, and a supporting frame projecting into the plane of the sash with which the bearing heads are 90 pivotally connected.

3. A swinging sash divided longitudinally into separated sections, each section comprising a plurality of units transversely arranged side by side, a plurality of supporting heads located intermediate the separated sash sections, oppositely disposed arms carried by the heads, said arms being interposed 100 between the adjacent sides of succeeding section units, and a supporting frame with which the heads are pivotally connected.

4. A swinging sash comprising separated sections, rigidly connected one to the other in spaced relation, and a supporting frame extending transversely through the space intermediate the sash sections with which the intermediate connections of the sash sections are pivotally engaged.

5. A swinging sash comprising two separated sections rigidly connected one to the other, a supporting structure and pivotal connections between the sash and supporting structure projecting in the plane of the sash 120 intermediate the sections, and pivotal connections with the supporting structure so arranged that the sash will oscillate upon an axis intermediate the sash sections.

6. A swinging sash comprising separated sections connected one to the other, each section comprising a plurality of separate units arranged side by side and connected one with the other, and a supporting frame for the sash projecting into the window space 130

and intermediate the sash sections into the plane of the sash with which the sash is pivotally connected.

7. A swinging sash comprising separated sections connected one to the other, a bearing head oppositely disposed arms carried by the head and located intermediate the units, and additional arm carried by the head in angular relation with the first mentioned arms, and a supporting structure with which the head is pivotally connected.

8. A swinging sash comprising two separated sections connected one to the other, a supporting structure having a transverse recessed bar, and bearing heads carried intermediate the sash sections pivotally engaged within the recesses of the transverse bar of the supporting structure.

9. A swinging sash, supporting heads carried thereby, bearing heads arranged in pairs between which the supporting heads of the sash are pivotally engaged, and supporting struts for the bearing heads offset in relation therewith.

10. A supporting strut, a bearing head carried thereby in offset relation, a swinging sash pivotally engaged with the offset bearing head, said sash being recessed to permit the offset bearing head to project into the plane of the sash.

11. A supporting structure comprising bearing heads arranged in pairs, transverse connecting members between successive pairs of bearing heads, a swinging sash, and supporting heads carried by the sash adapted to be pivotally engaged between the bearing heads of each pair.

12. A frame, a transverse bar separated into a plurality of sections, struts supporting said transverse bar, and a swinging sash having supporting heads pivotally engaged between the adjacent ends of the several sections of the transverse bar.

13. A swinging sash having an elongated opening coincident with the axis of oscillation, a plurality of supporting heads located within said opening and spaced apart, supporting frame members located within the opening intermediate the supporting heads with which the heads are pivotally connected, and supporting struts engaged with the frame members.

14. A swinging sash having an elongated opening therein coincident with the axis of oscillation divided by transverse supporting heads, a supporting structure comprising struts, bearing heads arranged in pairs and carried in offset relation with the struts, said bearing heads extending on opposite sides of the supporting heads of the sash, and closure members for the sash opening extending from one pair of bearing heads to the next succeeding pair of bearing heads.

15. A supporting structure comprising a plurality of frame members arranged in

axial alignment but spaced apart, supporting struts for said frame members, a swinging sash having an elongated opening coincident with the axis of oscillation, a plurality of supporting heads located transversely within said opening, said heads being pivotally engaged between the adjacent ends of the frame members, the construction being such that the frame members will project within the sash opening between the supporting heads.

16. A window frame for a swinging sash having a transverse bar having spaced recesses therein, and a swinging sash having spaced bearing heads intermediate the ends of the sash pivotally engaging in the recesses of the transverse frame bar, substantially as specified.

17. A swinging sash, pivotal bearings for said sash located at points throughout its length, and supporting struts for said bearings projecting into the window space from one side only thereof in relation with which the said bearings are offset.

18. A frame, a plurality of cylindrical supporting members arranged transversely in relation with the frame, in axial alignment one with the other but spaced apart, bearing heads located at the adjacent ends of the cylindrical supporting members, and struts upon which said members are supported.

19. Supporting struts projecting into the window space, supporting heads arranged in pairs carried by said struts in positions offset in relation with the struts, a swinging sash, and bearing heads carried thereby projecting between the supporting heads of each pair with which they are pivotally engaged.

20. A swinging sash having a space therein coincident with the axis of oscillation, a frame for the sash having a stationary transverse bar projecting within the recess in the sash and pivotal connections between the sash and bar intermediate the ends of the sash.

21. A bearing head, two supporting struts engaged with the head and arranged angularly one with the other, the bearing head being offset in relation with the strut connections, a swinging sash and a supporting head carried thereby pivotally engaged with the bearing head.

22. A swinging sash, a bearing head with which the sash is pivotally connected, and a plurality of adjustable supporting struts connected with the bearing head in positions offset in relation with the pivotal connection of the sash.

23. A swinging sash, supports therefor comprising bearing heads arranged in pairs, lateral wings carried by the bearing heads, supporting struts engaged with the lateral wings of each pair of bearing heads, and

supporting heads upon the sash pivotally engaged between the bearing heads forming each pair.

24. A swinging sash, supports for said sash comprising a plurality of bearing heads located at intervals throughout the length of the sash, adjustable supporting struts engaged with the bearing heads, and supporting heads carried by the sash pivotally engaged with the bearing heads, the construction and arrangement being such that by the adjustment of the adjustable struts, any one of the bearings of the sash may be independently varied in its relation with the remaining bearings.

25. A plurality of bearing members arranged in spaced relation throughout a window space, space bars intermediate successive bearing members, struts supporting the bearing members and space bars at points within the window opening, the bearing members, space bars and struts being

connected one to the other to form a rigid supporting structure, and a swinging sash pivotally connected with the bearing members.

26. A swinging sash, a supporting member extending across the window space to which the swinging sash is pivotally connected, and struts supporting said sash supporting member at points within the window opening.

27. A swinging sash, a supporting structure therefor comprising a plurality of struts and intermediate transverse connections between the struts, said struts and connections being located within the window opening controlled by the swinging sash.

In testimony whereof, I have hereunto set my hand this 4th day of February, 1914.

WILLIAM BAYLEY.
